George Fowler

United States Patent Office.

GEORGE FOWLER, OF CLAVERACK, NEW YORK.

Letters Patent No. 95,787, dated October 12, 1869.

IMPROVED RAILWAY-TRACK CLEAVER.

The Schedule referred to in these Letters Patent and making part of the same.

Be it known that I, GEORGE FOWLER, of the town of Claverack, in the county of Columbia, and State of New York, have invented a new and useful Machine for Clearing the Snow from Between the Rails of Railroad-Tracks, which I denominate a "Railroad-Track Flanger and Cleaner;" and I do hereby declare that the following is a full, clear, and exact description of the construction and operation of the same, reference being had to the annexed drawings, making a part of this specification, in which—

Figure 1 is a perspective view of the entire machine.

The nature of my invention consists in attaching to the platform of the rear car of a train one or two long diverging metallic shovels, supported on springs, so that the heels or lower ends of the shovels will scrape up the snow from the track, and, by the velocity of the train or car, throw and deposit it outside the rails.

To enable those skilled in the art to make and use my invention, I will proceed to describe its construction and operation.

To the rear end of a platform-car, A, I attach a strong beam, B, by means of a hinge or hinges, or their equivalent, at the back edge of the beam, so that it may be vibrated, or its front edge, with its attachments of springs and shovels, may be raised and lowered at pleasure.

To the under side of this beam B, I attach a suitable number of metallic spring bars or supports, e e e, &c., twisted at or near the middle, so as to present their narrow edges to the snow.

To the lower ends of these springs are attached one or two diverging metallic shovels, or winged scoops, C C, standing at such inclination or angle with the surface of the road as to receive the snow at the heel or lower end, and conduct it, through the aid of the motion of the car, out at the top or upper extremity of the shovels, and deposit it outside of the track.

On a double track, one wide shovel only is to be employed, throwing the snow all from each track in one direction—all on the outside of each track.

When employed for cleaning the streets of a city, or clearing the snow from street-railroads, sleighs may be attached or conducted alongside.

With this apparatus or machine, the snow may be cleared out to the width of a foot inside each rail, or it may be taken out in an elliptic curve or rounded bank, from rail to rail.

The springs D D are flanges, designed for clearing the snow from inside the rails, closer than the shovels can safely be made to run.

The shovels may be separated in the middle, or made so narrow as to leave the snow in the middle of the track, and only remove it near the rails.

The beam B is locked down firmly to the car by elevating the eccentric or cam-lever f, and when it is required to elevate the shovels, so as to pass over switches or in backing the car, this lever is depressed, relieving the beam and the upright handle e, drawn backward.

But I do not intend to confine myself to these simple devices for working the beam B. Other and more efficient levers may be used for this purpose.

I contemplate employing only one lever to raise and lower and lock this beam.

The rods a a are employed to support the outer lower corners of the shovels, or scoops C C.

This entire machine or apparatus I believe to be new, and

I, therefore, claim as my invention, and desire to secure by Letters Patent of the United States—

1. The combination and arrangement of beam B, shovels C C, springs e e e, &c., in the manner, or substantially in the manner and for the purpose herein set forth.

2. The employment, in combination with the above, of the flanges or springs D D, substantially as and for the purpose described.

3. Attaching the above-described several parts and devices, when combined and arranged substantially as set forth, to the rear end of a railway-truck or car, substantially in the manner and for the purpose herein set forth.

GEORGE FOWLER.
